[57] **CLAIM**

The ornamental design for a bandage, as shown.

DESCRIPTION

FIG. 1 is a top perspective view of a bandage showing one embodiment of our new design;

FIG. 2 is a top plan view of the embodiment of FIG. 1; FIG. 3 is a bottom plan view of the embodiment of FIG. 1;

FIG. 4 is a side elevation of the embodiment of FIG. 1;

FIG. 5 is an elevation of the side opposite FIG. 4;

FIG. 6 is an end elevation of the embodiment of FIG. 1;

FIG. 7 is an elevation of the end opposite FIG. 6;

FIG. 8 is a top perspective view of another embodiment of a bandage showing our new design;

FIG. 9 is a top plan view of the embodiment of FIG. 8;

FIG. 10 is a bottom plan view of the embodiment of FIG. 8;

FIG. 11 is a side elevation of the embodiment of FIG. 8;

FIG. 12 is an elevation of the side opposite FIG. 11;

FIG. 13 is an end elevation of the embodiment of FIG. 8; and

FIG. 14 is an elevation of the end opposite FIG. 13.
